UNITED STATES PATENT OFFICE.

GEORGE C. HURT, OF BLACKSTONE, VIRGINIA.

COMBINED CAP AND FUNNEL FOR RADIATOR-FILLING TUBES.

1,339,562.

Specification of Letters Patent. Patented May 11, 1920.

Application filed August 21, 1918. Serial No. 250,843.

To all whom it may concern:

Be it known that I, GEORGE C. HURT, a citizen of the United States, residing at Blackstone, in the county of Nottoway and 5 State of Virginia, have invented new and useful Improvements in Combined Caps and Funnels for Radiator-Filling Tubes, of which the following is a specification.

This invention relates to a combined cap 10 and funnel for the filling tube or neck of an automobile radiator which is so constructed that when applied to said tube in one position it will serve as a convenient means for directing water into the tube 15 and when applied in another or reversed position to said tube it will operate as a cap therefor in order to exclude foreign matter therefrom.

It is the object of this invention to provide 20 a combined cap and funnel for this purpose which is simple and inexpensive in construction and efficient in operation and which can be readily applied to the filling tube for performing either of the above described functions.

In the accompanying drawings:

Figure 1 is a vertical section showing my combined cap and funnel applied to the filling tube of a radiator in such manner 30 that the same will serve as a cap therefor. Fig. 2 is a similar view showing the same applied to the filling tube in such position that it serves as a water funnel for the same. Fig. 3 is a plan view of a combined 35 cap and funnel embodying my invention.

Similar characters of reference indicate corresponding parts throughout the several views.

1 represents the upright filling tube or 40 neck of a radiator such as are commonly employed on automobiles for cooling the water circulated around the heated parts of the gas engine which drives the automobile. In the particular form of this filling 45 tube shown in the drawings, the same is provided in the upper end of its bore with an internal screw thread 2 and at the lower end of this thread with an upwardly-facing annular shoulder 3, although my invention 50 is applicable to other forms of filling tubes. Within this filling tube is arranged the upper portion of an overflow or vent pipe 4 through which any excess water which 55 may be poured into the radiator as well as any steam or vapors which may be generated in the radiator are permitted to flow

or escape to the exterior of the same. As shown in Figs. 1 and 2, this overflow tube terminates at its upper end a short distance above the shoulder of the filling tube. 60

The combined cap and water funnel embodying my invention and designed more particularly for coöperation with this construction of filling tube and the arrangement of the over-flow pipe therein, is constructed 65 as follows:

5 represents an inner annular wall preferably of cylindrical or tubular form which is provided on its periphery adjacent to one end thereof with an external screw thread 70 6 which is adapted to engage with the internal screw thread of the filling tube. At its threaded end this inner wall is closed by a head or diaphragm 7 which latter, in the form shown in Figs. 1 and 2, is preferably 75 dished inwardly so that upon screwing this inner wall into the filling tube until the respective end of the same engages with the shoulder 3 of the tube, said head will be spaced from the upper end of the overflow 80 pipe and thereby permit the free escape of water as well as steam or vapor from the upper part of said filling tube outwardly through the overflow pipe. Adjacent to that 85 end of the inner wall opposite to that which is closed by the head 7, this wall is provided with a water inlet which is preferably constructed in the form of a plurality of openings 8 which are arranged in an annular row around this inner wall and in such position 90 that when this device is applied to the filling tube to serve as a cap, the space within the inner wall will be cut off from communication with the interior of the filling tube and thus exclude the entrance of any foreign 95 matter into the radiator.

9 represents an outer annular wall which is preferably constructed of conical or tapering form and arranged around the inner wall. This outer wall is preferably of such 100 length that its large end extends a considerable distance beyond that end of the inner wall which is closed by the head 7, and the opposite end of this inner wall is connected with the corresponding small end 105 of the outer wall in such manner that a seat is formed for engaging the upper end of the filling tube and enabling the space within the outer wall to be placed in communication with the interior of the filling tube 110 when this device is to be used as a water funnel for the radiator, as shown in Fig. 2,

In the preferred construction, the small end of the outer wall is connected with the corresponding end of the inner wall by a conical web 10 which tapers inwardly and 5 in a direction opposite to the taper of the outer wall, and the outer face of this web is provided with an annular packing ring 11 of rubber or similar elastic material which is of corresponding tapering form and constitutes an elastic seat which, upon engaging 10 with the upper end of the filling tube, as shown in Fig. 2, forms a tight joint therewith, so that upon pouring water into the large end of the outer wall in this position of the parts, this water will be conducted 15 through the openings in the inner wall to the interior of the filling tube without liability of any of this water leaking past the joint between the web and the tube and spilling 20 onto the adjacent external parts of the radiator. It is therefore possible to always keep the radiator in a clean condition instead of incurring the liability of spotting the radiator. When this device is employed 25 as a cap for the radiator tube, the outer wall flares downwardly around the filling tube and produces a neat and finished appearance of the same.

By combining the cap and filling funnel 30 in this manner, it is unnecessary to employ separate devices for this purpose as is commonly the case and it also positively prevents loss of the funnel as frequently occurs when the same is made separate from the 35 cap, so that means for properly filling the radiator with water are always available.

In the preferred construction of this device, the inner and outer walls, the head and the web are made from a single sheet 40 of metal by spinning, stamping or otherwise, but if desired these parts may be constructed in any other suitable manner.

I claim as my invention:

1. A combined cap and funnel for a radiator filling tube, comprising an inner annular wall provided with openings in its side, a head closing one end of the space within said inner wall, and an outer annular wall connected at one of its ends with the 45 opposite end of said inner wall, said inner wall being provided with screw threads for attaching the same to said radiator filling tube.

2. A combined cap and funnel for a radiator filling tube, comprising an inner annular wall provided with openings in its side, a head closing one end of the space within said inner wall, and an outer annular 50

wall surrounding said inner wall and connected at one of its ends with the opposite end of said inner wall, said inner wall being provided with screw threads for attaching the same to said radiator filling tube. 60

3. A combined cap and funnel for a radiator filling tube, comprising an inner annular wall provided with openings in its side, a head closing one end of the space within said inner wall, and an outer conical wall surrounding said inner wall and connected at its small end with the opposite end 65 of said inner wall, said inner wall being provided with screw threads for attaching the same to said radiator filling tube. 70

4. A combined cap and funnel for a radiator filling tube, comprising an inner annular wall provided with openings in its side, a head closing one end of the space within said inner wall, an outer conical wall surrounding said inner wall, and a conical web connecting the small end of said outer 75 wall with the opposite end of said inner wall, said inner wall being provided with screw threads for attaching the same to said radiator filling tube. 80

5. A combined cap and funnel for a radiator filling tube, comprising an inner annular wall provided with openings in its side, a head closing one end of the space within said inner wall, an outer conical wall surrounding said inner wall, a conical web 85 connecting the small end of said outer wall with the opposite end of the inner wall, and a packing arranged on the outer face of said web. 90

6. A combined cap and funnel for a radiator filling tube, comprising an inner annular wall provided with openings in its side, a head closing one end of the space within said inner wall, and an outer annular wall surrounding said inner wall and connected at one of its ends with the opposite end of said inner wall, said inner wall being provided on its periphery with an external screw thread adapted to engage with the screw thread of said filling tube. 95

7. A combined cap and funnel for a radiator filling tube, comprising an inner annular wall provided with openings in its side, a head closing one end of the space within said inner wall, and an outer annular wall surrounding said inner wall and connected at one of its ends with the opposite end of said inner wall, said head being dished inwardly to clear the overflow pipe 100 in said filling tube. 110

GEORGE C. HURT.
